US0D1069676S

(12) **United States Design Patent** (10) **Patent No.:** **US D1,069,676 S**
(45) **Date of Patent:** **** Apr. 8, 2025**

(54) **STORAGE COVER**

(71) Applicant: **Polaris Industries Inc.**, Medina, MN (US)

(72) Inventor: **Michael Hritz**, Medina, MN (US)

(73) Assignee: **Polaris Industries Inc.**, Medina, MN (US)

(**) Term: **15 Years**

(21) Appl. No.: **29/955,252**

(22) Filed: **Jul. 31, 2024**

Related U.S. Application Data

(62) Division of application No. 29/776,439, filed on Mar. 30, 2021, now Pat. No. Des. 1,045,399.

(57) **CLAIM**

The ornamental design for a storage cover as shown and described.

DESCRIPTION

FIG. 1 is a left, front perspective view of a storage cover of the present application;

FIG. 2 is a front elevational view of the storage cover of FIG. 1;

FIG. 3 is a rear elevational view of the storage cover of FIG. 1;

FIG. 4 is a left side elevational view of the storage cover of FIG. 1;

FIG. 5 is a right side elevational view of the storage cover of FIG. 1;

FIG. 6 is a top plan view of the storage cover of FIG. 1; and, FIG. 7 is a bottom plan view of the storage cover of FIG. 1. The portions of the storage covers shown in broken lines form no part of the claimed design.

1 Claim, 5 Drawing Sheets
